CLAIM

The ornamental design for an identification tag unit for
electrical wire ends, as shown and described.

DESCRIPTION

FIG. 1 is a top plan view of an identification tag unit for
electrical wire ends showing my new design;

FIG. 2 is a front elevational view thereof;

FIG. 3 is a bottom plan view thereof;

FIG. 4 is a rear elevational view thereof;

FIG. 5 is a right side elevational view thereof;

FIG. 6 is a left side elevational view thereof;

FIG. 7 is a perspective view thereof, with the broken
line showing for illustrative purposes only and forming
no part of the claimed design; and,

FIG. 8 is a sectional view taken along line 8—8 of FIG.
2.
